UNITED STATES PATENT OFFICE.

CARL C. KUSTERER, OF GRAND RAPIDS, MICHIGAN.

DRAW TABLE.

Application filed March 13, 1922. Serial No. 543,180.

This invention relates to improvements in draw tables.

The objects of the invention are:

First, to provide an improved draw table in which the parts of the top are effectively maintained in separated relation while the leaves are being withdrawn or pushed in.

Second, to provide an improved sliding means for such structure.

Third, to provide an improved lock means for the parts.

Further objects, and objects relating to structural details will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawings, forming a part of this specification, in which:

Fig. I is a side elevation view of the upper part of a draw table embodying the features of my invention.

Fig. II is an end view of the same.

Fig. III is a side elevation view of the right hand portion of the table appearing in Fig. I showing the leaves and slide partially withdrawn and indicating by dotted lines the relation of the parts when the table is extended.

Fig. IV is a detail longitudinal vertical central sectional elevation view taken on a line corresponding to line 4-4 of Figs. V and X.

Fig. V is a detail plan view of the right hand portion of the table appearing in Fig. I with the leaves drawn out, the left-hand portion being broken away and the table top being partially broken away and removed to show details of construction.

Fig. VI is an enlarged detail sectional view on a line 6-6 of Fig. V showing particularly details of the slide and its automatic top support extension with the leaf and slide in extended position.

Fig. VII is a similar sectional view showing the relation of the parts when the table is in closed position.

Fig. VIII is an enlarged detail sectional view taken on a line 8-8 of Figs. I, IV, V, VI, VII, IX and X showing the retaining means for the top.

Fig. IX is an enlarged detail sectional view taken on a line corresponding to line

9-9 of Figs. V and VIII and X, showing the said top retaining means.

Fig. X is a detail inverted reduced plan view of the table top showing the position of the slide contact buttons and the top retaining and locking means.

In the drawings, similar reference characters refer to similar parts throughout the several views, and the sectional views are taken looking in the direction of the little arrows at the ends of the section lines.

The numbered parts of the drawing will be considered by their numerals. 1 are the side rails of the table. 2 are the corner posts. 3 are the end rails. 4 is the central cross bar between the side rails being notched at 5 near each end as seen in Fig. VII.

6 is the table top. 7 is the central cross supporting cleat of the said table top. 8 are the fastening means for retaining the table top in central position. Each is provided with a downwardly extending arm 9 just within the corresponding side rail 1 having the longitudinal keyhole slot 10 through which extends the bolt 11 provided with a retaining nut 11' on its inner end as seen in detail in Figs. VIII and IX. A dowel pin 12 is secured to the top cross cleat near each end and projects down from the under side of the said cross cleat 7 and engages adjustably in the hole 13 for partial withdrawal therefrom in the side rail 1. These parts co-operate. The dowel alone cannot be effectively retained and the slotted arm with pin in slot will not play freely if made a close fit to guide the parts.

14 and 15 are the extension draw leaves disposed under the ends of the table top 6 when the table is in closed position as indicated in Figs. I and IV. 16 and 17 are the cross cleats under the outer ends of the leaves 14 and 15 respectively. 18 and 19 are oppositely disposed pairs of slides which are secured to the under sides of their respective leaves 14 and 15 and travel in notches 18' and 19' in the end rails, the same riding upon the bottoms of the said notches.

The under sides of these slides are inclined so that as the slides are drawn out the respective leaves 14 and 15 carried thereby will be gradually raised to the position indicated by the dotted lines in Fig. III. The inner end of each slide is cut down as at 18'' and 19'' to receive the cross cleat 7 when the leaves are drawn out. The inner ends are provided with stops 20 having en-

gaging hooks 21 to pass under the central bar 4 and engage in the notches 5 of the cross bar 4, the said stops being retained in place by screws 22.

5 An automatic slidable support block 23 for the table top is disposed and slides in the recess 25 in the upper side of each slide as seen in Figs. VI and VII. This auxiliary slide block 23 is rounded at 24 on its inner end. A stop pin 27 is disposed to limit the inward movement of each block. A stop block 23' limits the outward movement.

A pin 230 in slot 231 in the block 23 guides and retains the same in the slot 25. 15 A plunger 232 comprising a wire nail with a large head reacts against spring 233 disposed in the bore or socket 234 in the block 23' and shoots the auxiliary slide 23 out against the stop 27 whenever it is disengaged from the sliding parts.

Slide contact buttons 28 suitably rounded on their contact surfaces are placed on the under side of the cross cleat 7 in position to contact with the upper sides of the slides 25 and support the table top out of contact with the leaves, while the same are being moved out and in. This prevents injury to the tops of the draw leaves. When the slides are pulled out to the limit as indicated in Fig. 30 VII these buttons drop into recesses 29 formed in the tops of the slides, which permits the top 6 to drop down directly into contact with the draw leaves when same are pushed in. The contact buttons 28 rest upon the top of the slide 23 when the draw leaf is being drawn out and contacts with the extension block 23, thus supporting the table top entirely out of contact with the leaf until it is entirely withdrawn from beneath the top. When the leaf reaches its outermost position the weight of the top on the rounded portion 24 causes block 23 to move automatically from beneath the contact buttons 28 and permits the top to drop down into place. Slight clearance is provided for and the leaves can then be closed up to the top. When the draw leaves are being pushed in, the table top is, of course, raised. The slide block 23 is carried out 45 to place by the spring 233 and the anti-friction button 28 rides thereon and carries the table top, slightly elevated, until the draw leaf is shoved into position when the button drops into the depression 29 bringing 50 the parts again firmly together.

Having thus described my invention, what I claim as new and desire to secure by Letters Patent is:

60 1. In a draw table structure, the combination with the table framework of a top with central cross cleat thereunder, downwardly projecting contact buttons disposed upon the under side of the central cross cleat in position to ride upon the upper sides of the draw leaf slides, a cross bar in the center 65

of the table, draw leaves adapted to be disposed underneath each end of the said table top, slides with inclined surfaces riding in notches in the table ends and secured to the said draw leaves, having cutaway portions 70 on their upper sides at the inner ends to accommodate the central cleat and provided with longitudinal ways in their upper surfaces at the beginning of the cutaway part and notches on their upper sides in proximity to the draw leaves to receive said contact buttons, a horizontally movable slide extension, having rounded inner upper end, disposed in the way in the top of each slide 75 in proximity to the cutaway portion adapted to automatically retract when the leaves are fully drawn to permit the central cleat and table top to drop to position when the leaves are withdrawn, spring means to hold said extension slide yieldingly in position, and hooked stops at the inner ends of said slides 80 to engage said cross bar, coacting as specified.

2. In a draw table structure, the combination with the table framework of a top with central cross cleat thereunder, downwardly projecting contact buttons disposed upon the under side of the central cross cleat in position to ride upon the upper sides 90 of the draw leaf slides, a cross bar in the center of the table, draw leaves adapted to be disposed underneath each end of the said table top, slides with inclined surfaces riding in notches in the table ends and secured to the said draw leaves, having cutaway portions 95 on their upper sides at the inner ends to accommodate the central cleat and provided with longitudinal ways in their upper surfaces at the beginning of the cutaway part, and notches on their upper sides in 100 proximity to the draw leaves to receive said contact buttons, a horizontally movable slide extension, having rounded upper end, disposed in the way in the top of each slide 105 in proximity to the cutaway portion adapted to automatically retract when the leaves are fully drawn to permit the central cleat and table top to drop to position when the leaves are withdrawn, and hooked stops at the 110 inner ends of said slides to engage said cross bar, coacting as specified.

3. In a draw table structure, the combination with the table framework of a top with central cross cleat thereunder, downwardly projecting contact buttons disposed 115 upon the under side of the central cross cleat in position to ride upon the upper sides of the draw leaf slides, draw leaves adapted to be disposed underneath each end of the said table top, slides with inclined surfaces riding in notches in the table ends and secured to the said draw leaves, having 120 cutaway portions on their upper sides at the inner ends to accommodate the central cleat and provided with longitudinal ways in 125 the center of the table, draw leaves adapted to be disposed underneath each end of the said table top, slides with inclined surfaces riding in notches in the table ends and secured to the said draw leaves, having cutaway portions on their upper sides at the inner ends to accommodate the central cleat and provided with longitudinal ways in 130

- their upper surfaces at the beginning of the cutaway part, and notches on their upper sides in proximity to the draw leaves to receive said contact buttons, a horizontally 5
movable slide extension having rounded inner upper end disposed in the way in the top of each slide in proximity to the cutaway portion, adapted to automatically retract when the leaves are fully drawn to 10
permit the central cleat and table top to drop to position when the leaves are withdrawn, and spring means to hold said extension slide yieldingly in position, coacting as specified. 15
4. In a draw table structure, the combination with the table framework of a top with central cross cleat thereunder, downwardly projecting contact buttons disposed upon the upper side of the central cross 20
cleat in position to ride upon the upper sides of the draw leaf slides, draw leaves adapted to be disposed underneath each end of the said table top, slides with inclined surfaces riding in notches in the table ends and secured to the said draw leaves, having cutaway portions on their upper sides at the inner ends to accommodate the central cleat and provided with longitudinal ways in their upper surfaces at the beginning of the cutaway part, and notches on their upper sides in proximity to the draw leaves to receive said contact buttons, and a horizontally movable slide extension having rounded inner upper end disposed in the way in the top of each slide in proximity to the cutaway portion adapted to automatically retract when the leaves are fully drawn to permit the central cleat and table top to drop to position when the leaves are withdrawn, coacting as specified. 30
5. In a draw table structure, the combination with the table framework of a top with a central cross cleat thereunder, downwardly projecting contact buttons disposed upon the under side of said central cross 35
45
- cleat in position to ride upon the upper sides of the draw leaf slides, draw leaves adapted to be disposed underneath each end of the said table top, slides with inclined surfaces riding in notches in the table ends and secured to the said draw leaves with cutaway portions on their upper sides at the inner ends to accommodate the central cross cleat and provided with longitudinal ways in their upper surfaces at the beginning of the cutaway part, a horizontally movable slide extension having rounded inner upper end, disposed in the way in the top of each slide in proximity to the cutaway portion adapted to permit the central cleat and table top to drop to position when the leaves are withdrawn, and spring means to hold said extension slide yieldingly in position. 50
